UNITED STATES PATENT OFFICE.

JAMES F. THAYER, OF PROVIDENCE, RHODE ISLAND.

BUTTON-SETTING TOOL.

SPECIFICATION forming part of Letters Patent No. 445,304, dated January 27, 1891.

Application filed November 19, 1890. Serial No. 371,914. (No model.)

To all whom it may concern:

Be it known that I, JAMES F. THAYER, a citizen of the United States, residing at Providence, in the county of Providence and State 5 of Rhode Island, have invented certain new and useful Improvements in Fastener-Attaching Instruments; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to instruments or tools for attaching buttons to fabrics by means of pronged fasteners, and has for its object to provide a device whereby the buttons are quickly and securely attached, all as will be 20 hereinafter fully described.

Figure 1 represents my improved instrument with button and fastener in position for use. Fig. 2 is a front end view of the same with button and fastener removed. Fig. 3 is a like 25 view with fastener-holding spring removed. Fig. 4 is a side sectional view of the front end of the upper member of the instrument. Fig. 5 is a bottom plan view of the same.

As organized in the present instance, *a* and 30 *b* represent, respectively, the upper and lower members of a plier-like instrument pivoted at *c* and operated by the handles *d* and *e*, as is usual.

d^x represents the button, and *d*² the fastener for attaching same.

The member *a* is provided at its front end with a fastener-holder *a'*, secured in the present instance to said member by the screw *a*², or the same may be formed integral with said 40 member. The fastener-holder *a'* is provided with a rectangular groove *a*³ for the reception of the crown or arch of a fastener wrought in the front and lower end thereof at right angles to the length of the instrument, in form 45 approximating the contour of the crown or arch of the fastener. The groove *a*³ is dovetailed or V-shaped in cross-section, its rear wall being parallel with the back side of the fastener-holder *a'* and angled outward to the 50 front of said fastener-holder, as fully shown in Figs. 4 and 5 of the drawings, and is of a depth somewhat less than the diameter of the

wire of the fastener, so that the spring *b'*, hereinafter described, will clamp the crown or arch of the fastener when placed in said 55 groove. The fastener-holder *a'* is also provided with a cross-slot *a*⁴, extending across the groove *a*³ to receive the eye of the button *d'*, as shown in Figs. 3 and 5 of the drawings. The front face of the fastener-holder *a'* is 60 further provided with a flat spring *b'*, previously mentioned, secured at the upper part thereof by means of the screw *a*², said spring being also cross-slotted in its lower end correspondingly with the slot *a*⁴ of the fastener- 65 holder *a'*, said slot being also adapted to straddle the eye of the button.

The member *b* is provided on its outer end with a clinching-die *c'*, wrought in the face thereof, for bending and clinching the legs of 70 the fastener in contact.

In operation the crown or arch of the fastener *d*², with button *d'* loosely suspended thereon, is inserted into the groove *a*³ back of the spring *b'*, said spring clamping said 75 crown or arch flatwise and holding the fastener firmly in position with its legs exposed and standing at right angles to the length of the instrument directly over and opposite the clinching-die *c'* of the member *b*, as fully 80 shown in Fig. 1. The fabric being placed on the die *c'*, the two members of the instrument are brought together, the legs of the fastener are pressed through the fabric, and on coming in contact with the die *c'* are firmly 85 clinched on the under side thereof.

It will be observed that the side of the crown or arch of the fastener rests against the rear wall of the groove *a*³ when in position for clinching, the spring *b'* holding it in 90 place. The upper end of the fastener abuts or wedges against the angled portion of the groove *a*³, said angled portion taking the end-wise strain incident to the clinching operation and rendering it impossible for the fastener to move forward in said groove. It will also be observed that the fastener is held and attached independent of the action of the button, as the said button rests loosely on the fastener in attachment. In this respect 95 the device is admirably adapted for inserting fasteners where buttons are not required, in which case the cross-slot *a*⁴ in the fastener-holder and spring may be omitted.

I have shown and described my improvement as applied to a hand-plier-like instrument. It is evident the same may be equally adapted to organized machines to be operated by foot or other suitable power.

Having described my invention, I claim—

- 5 1. An instrument for attaching pronged fasteners to fabrics, one member of which is provided with a die for bending and clinching the legs of the fastener, the opposite member having a vertical and transverse groove to receive the crown or arch of the fastener, and a spring to retain the crown or arch in said groove, substantially as set forth.
- 10 15 2. An instrument for attaching pronged fasteners to fabrics, one member of which is provided with a die for bending and clinching the legs of the fastener, the opposite member being provided with a rectangular
- 20 20 **V**-shaped groove and a transverse groove substantially at right angles thereto and further provided with a flat spring, substantially as and for the purpose set forth.

3. In an instrument for attaching fasteners to fabrics, and in combination with the clinching member thereof, the fastener-holding member having a cross-slotted **V**-shaped groove to receive the crown or arch of the fastener, and a bifurcated spring to clamp said crown or arch flatwise in said groove, substantially as specified.

4. An instrument for attaching fasteners to fabrics, one member of which is provided with a groove to receive the crown or arch of the fastener, and a flat spring to clamp said crown or arch flatwise in said groove, the opposite member being provided with clinching dies for bending and clinching the legs of the fastener, substantially as set forth.

In testimony whereof I affix my signature in the presence of two witnesses.

JAMES F. THAYER.
